United States Patent Office.

GEORGE GREGORY AND F. B. MORSE, OF NEW HAVEN, CONNECTICUT,
ASSIGNORS TO THEMSELVES AND W. H. COOPER, OF SAME PLACE.

Letters Patent No. 63,792, dated April 16, 1867.

IMPROVEMENT IN JOINTS FOR CARRIAGE-TOP BRACES.

The Schedule referred to in these Letters Patent and making part of the same.

TO ALL WHOM IT MAY CONCERN:

Be it known that we, GEORGE GREGORY and F. B. MORSE, of New Haven, in the county of New Haven, and State of Connecticut, have invented a new Improvement in Stump Joint for Carriages; and we do hereby declare the following, when taken in connection with the accompanying drawings, and the letters of reference marked thereon, to be a full, clear, and exact description of the same, and which said drawings constitute part of this specification, and represent, in—

Figure 1, a perspective view, the joint in position as when open.

Figure 2, a perspective view when closed.

Figure 3, a sectional view; and in

Figures 4 and 5, the two parts detached.

This invention relates to an improvement in what is termed a stump joint for carriages, that is to say, the joint in the braces which supports the top in an upright position or permits it to drop when the joint is open, and consists in the peculiar formation of the joint whereby it is much strengthened and its durability increased at little or no additional expense.

To enable others to construct and use our improvement, we will proceed to describe the same as illustrated in the accompanying drawings.

A and B are the two parts of the joint; upon the one, B, is formed an ear, C, and upon the other an ear, D, in outward appearance corresponding to each other and to the common stump joint. Upon the one ear, C, is formed a projecting stud, *a*, as seen in figs. 3 and 4, in the other ear, D, is formed a recess, as seen in fig. 5, corresponding to the projection *a* upon the other ear, so that when the two parts are placed together, the projection upon the one will fit into the recess of the other, and form a square shoulder bearing, as seen in fig. 3, so that the whole strain of the joint comes upon the metal of the joint itself. A screw, *d*, passes through the centre to secure the parts together, but by the construction of the joint as described, no strain or wear whatever comes upon the rivet or screw (whichever it may be) which secures the two parts together. Heretofore the two ears have been formed so that the meeting surfaces lie flat face to face, the whole strain and wear coming upon the rivet or screw which secures the two parts together, consequently the joint is soon worn loose. Thus formed, the joint is ready for market. The braces are welded to each of the parts and formed so as to conform to the construction of the carriage top.

We do not wish to be understood as broadly claiming a joint formed by the stud upon one part fitting into the corresponding recess in the other, as such is common and well known. Our invention is simply for an improved article of manufacture.

Having thus fully described our invention, what we claim is new and useful, and desire to secure by Letters Patent, is—

The herein-described stump joint as an improved article of manufacture, consisting of the two parts A and B, upon the ear of one of which is formed a stud, *a*, and in the other a corresponding recess, so that the said stud forms the bearing or pivot for the joint, substantially as herein set forth.

GEORGE GREGORY,
F. B. MORSE.
